(57) **CLAIM**

I claim the ornamental design for a watertight container, as shown and described.

DESCRIPTION

FIG. 1 is an isometric front and right side view of the watertight container with its pivoting top portion open showing my design.

FIG. 2 is an isometric front and right side view of the watertight container with its pivoting top portion closed showing my design.

FIG. 3 is a front view thereof.

FIG. 4 is a back view thereof.

FIG. 5 is a right side view thereof; and,

FIG. 6 is a left side view thereof.

1 Claim, 5 Drawing SheetsFIG. 1

FIG. 2

FIG. 3

FIG. 4

FIG. 5

FIG. 6
